(57) **CLAIM**

The ornamental design for a leash connector, as shown and described.

DESCRIPTION

FIG. 1 is a first perspective view of a leash connector showing my new design as used for connecting a leash to an object, such as a surf craft.

FIG. 2 is a second perspective view thereof.

FIG. 3 is a front elevational view thereof. A rear elevational view of the design is a mirror image of the front elevational view.

FIG. 4 is a top plan view thereof. A bottom plan view of the design is identical to the top plan view.

FIG. 5 is a right side elevational view thereof.

FIG. 6 is a left side elevational view thereof; and,

FIG. 7 is a third perspective view thereof, shown from the same angle as the second perspective view, but showing the left side without any connecting device inserted therein.

The broken lines shown in the drawings are for environmental and illustrative purposes only and form no part of the claimed design.
